AUTOMATIC BUCKET TALLY

Frank D. Ellermeier, Swanton, Nebr.

Application March 9, 1932. Serial No. 597,782

1 Claim. (Cl. 235—94)

This invention aims to provide a simple but effective means whereby a tally may be kept, for instance, of the amount of liquid, such as gasoline, that is drawn out of a tank, the device being of peculiar utility when motor fuel is drawn from a delivery tank into cans, although the invention, of course, is not confined to that particular use.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:—

Fig. 1 shows in side elevation, a device constructed in accordance with the invention, parts being broken away;

Fig. 2 is a top plan, wherein parts are broken away;

Fig. 3 is a section on the line 3—3 of Fig. 2; Fig. 4 is an elevation of the body of the article, parts being in section;

Fig. 5 is a fragmental top plan showing a portion of the lever.

In carrying out the invention, there is provided a tubular body 1, preferably made of metal, and provided at its upper end with a recess 30, shown in Fig. 2. The body 1 is supplied at its upper end with a wrench head 2. On the lower end of the body 1 there is a reduced, threaded tip 3. Intermediate its ends, the body 1 is supplied with outstanding lugs 4. From one of the lugs 4, a short first shaft 5 projects, a long second shaft 6 projecting from the other lug, and these shafts being in axial alignment.

Below the shaft 5, the body 1 has an outstanding stud 7. Below the shaft 6, the body 1 carries an outstanding guide 8. The part 8 is called a guide, because, in it, a bevelled back stop pawl 9 has in and out straight line movement. The back stop pawl 9 does not rotate, upon its axis, since, as shown in Fig. 3, it is square or of other polygonal cross section. The back stop pawl 9 is urged outwardly by a compression spring 10, housed in the guide 8.

The numeral 11 designates a forked lever,

straddling the body 1. For convenience in assembly, the lever 11 may properly be made in two parts, as shown at 12 in Fig. 2 each of these parts carrying one of the constituent members of a supporting element or hook 14, the members of the hook, and, therefore, the entire lever 11, being held together by securing elements 15 of any desired kind, such as small bolts with lock washers. The lever 11 comprises a short first arm 17 and a long second arm 16, cooperating with the flat outer surfaces of the lugs 4. The first arm 17 is mounted to swing on the first shaft 5, and the second arm 16 is mounted to swing on the second shaft 6, both of these shafts being fixed to the lugs 4, or being formed integrally therewith. On its outer surface, and upon opposite sides of its fulcrum 6, the second arm 16 of the lever 11 has outwardly extended, oppositely-bevelled actuating pawls 18, which are shown in Fig. 5.

A circular tally disk 19 is journaled for rotation on the second shaft 6, outwardly of the second arm 16 of the lever 11. The tally disk 19 can slide longitudinally of the second shaft 6, but it is pressed inwardly by a compression spring 20, disposed about the said shaft, the inner end of the spring bearing against the tally disk 19, and the outer end of the spring bearing against a detachable abutment 21 on the shaft 6. The abutment 21 may be simply a washer and a cotter pin. Fig. 3 shows that, upon its inner surface, the tally disk 19 has a ratchet wheel 22, adapted to cooperate with the actuating pawls 18 of the second arm 16 of the lever 11, and with the back stop pawl 9. On its edge, the tally disk 19 has graduations 23 of any desired kind, such as numerals, and if the gasoline or other liquid is to be dispensed in five gallon units, the graduations 23 may read in steps of five. As the tally disk 19 is rotated, the graduations 23 appear, one at a time, through an opening in an index wing 24, shown in Fig. 2, the index wing being attached to the wrench head 2 of the body 1.

A return or lifting spring for the lever 11 is provided, and is marked by the numeral 25. This spring is coiled about the first shaft 5 on the body 1, one end of the spring being hooked underneath the first arm 17 of the lever 11, and the other end of the spring having a bearing in a notch in the stud 7. When the spring 25 lifts the lever 11 to the position shown in Fig. 1, the arch of the lever comes into engagement with the wrench head 2 of the body 1.

The numeral 26 indicates a spout, which may

be of any desired construction, and for the purposes of the present discussion, it will be presumed that gasoline is supplied to the spout 26 through an inlet 27 connected to the common 5 tank wagon (not shown). A valve mechanism 28, of any desired kind, and under the control of an operator, regulates the flow of gasoline through the spout 26.

The lower end of the spout 26 is threaded into 10 the recess 30 of the body 1, and, thus, the device is assembled with the spout. Some special makes of gasoline cans render it desirable to thread an extension 29 on the tip 3 of the body 1, but whether or not the extension 29 is used, is a 15 matter of choice.

In practical operation, the can to be filled is hung on the suspension element 14 of the lever 11, and the valve 28 is opened. The gasoline runs into the can, and after a time, the combined weight of the gasoline and the can is sufficient to swing the lever 11 downwardly, against the action of the return spring 25, until the arch of the lever engages the lower portion of the body 1. As the lever 11 swings downwardly, 20 the actuating pawls 18 on the second arm 16 of the lever turn the tally disk 19 on the second shaft 6, and one of the numerals 23 on the edge of the tally disk appears through the opening of the index wing 24. When the filled can 25 is lifted off the suspension element 14, the lever 11 swings upwardly on the shafts 5 and 6, under the action of the return spring 25. During this upward movement of the hooked end of the lever 11, the back stop pawl 9, under the action of the spring 10, cooperates with the ratchet wheel 22 on the inner surface of the tally disk 19, and holds the tally disk against retrograde rotation. Although the tally disk 19 thus is held against 30 backward rotation, the actuating pawls 18 of the lever 11 can click over the ratchet wheel 22. This is so, because the tally disk can slide outwardly, against the action of the spring 26, the spring 26 sliding the tally disk inwardly, as soon 35 as the actuating pawls 18 are in a position to get a new hold on the ratchet wheel 22.

It is clear that the construction and the operation of the device is such that a tally can be kept of the amount of liquid dispensed, it being necessary for the operator merely to glance 40

through the hole in the index wing 24, at the exposed numeral within the index wing, in a way which will be understood readily when Fig. 2 of the drawing is noted.

The tally mechanism does not interfere in any way with the dispensing of liquid when it is desired to keep no tally. The usual dispensing hose (not shown) may be connected to the tip 3 of the body 1, and the valve mechanism 28 may be manipulated to permit the gasoline to run through freely the spout 26, the body 1, and the hose, in the usual way.

Having thus described the invention, what is claimed is:—

In a device of the class described, a tubular body, oppositely disposed first and second shafts outstanding from the body, a forked lever spanning the body and comprising a suspension element, the lever embodying a first arm mounted to swing on the first shaft, and a second arm mounted to swing on the second shaft, an actuating pawl rigidly mounted on the second arm, a tally disk journaled on the second shaft and slideable inwardly and outwardly longitudinally of the second shaft, the tally disk being supplied on its inner side with a ratchet wheel, where-with the actuating pawl cooperates, a back stop pawl cooperating with the ratchet wheel and movably mounted on the body, spring means on the second shaft and engaging the tally disk to restrain yieldably the outward movement of the tally disk on the second shaft and let the actuating pawl click over the ratchet wheel when the lever is raised and whilst the back stop is engaged with the ratchet wheel to hold the tally disk against retrograde rotation, spring means for moving the back stop pawl outwardly, so that the back stop pawl will keep its hold on the ratchet wheel as the tally disk moves outwardly to let the actuating pawl click over the ratchet wheel, and spring means for raising the lever, the lever engaging the body to stop the downward movement of the lever when an article is hung on the suspension element of the lever, and the lever engaging the body when the lever is swung upwardly by the spring means for raising the lever.
